UNITED STATES PATENT OFFICE

163,976

CONTAINER FOR FISHHOOKS AND THE LIKE

Adolph K. Stevens, Buffalo, N. Y.

Application February 10, 1950, Serial No. 7,878

Term of patent 3½ years

(Cl. D58—11)

To all whom it may concern:

Be it known that I, Adolph K. Stevens, a citizen of the United States, residing at #197 North St., Apartment D-6, Buffalo, State of New York, have invented a new, original, and ornamental Design for a Container for Fishhooks and the Like, of which the following is a specification, reference being had to the accompanying drawing, forming a part hereof, in which:

Fig. 1 is a perspective view of a container for fishhooks and the like showing my new design.

Fig. 2 is a side elevation thereof.

Fig. 3 is a front elevation thereof.

Fig. 4 is a top plan view thereof.

I claim:

The ornamental design for a container for fishhooks and the like, as shown.

ADOLPH K. STEVENS.
